(57) **CLAIM**

The ornamental design for a bumper for a medical pump, as shown and described.

DESCRIPTION

FIG. 1 is a front, top, and right side perspective view of a first embodiment of a bumper for a medical pump, showing our new design;

FIG. 2 is a front side elevational view thereof;

FIG. 3 is a rear side elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front, top, and right side perspective view of a second embodiment of a bumper for a medical pump, showing our new design;

FIG. 9 is a front side elevational view thereof;

FIG. 10 is a rear side elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken line showing of the medical pump illustrates environment and forms no part of the claimed design.
